United States Patent Office

Des. 191,436
Patented Oct. 3, 1961

191,436

DOOR STOP

Edward F. Urich, 1100 SE. 12th Terrace,
Deerfield Beach, Fla.

Filed Mar. 6, 1961, Ser. No. 64,150

Term of patent 14 years

(Cl. D10—7)

Fig. 1.

Fig. 2.

FIG. 1 is a perspective view of a door stop showing in full lines the dominant feature of my new design, and FIG. 2 is an elevational view thereof in an inverted position.

I claim:

The ornamental design for a door stop, substantially as shown and described.
